LOUIS GUTEKUNST, OF PHILADELPHIA, PENNSYLVANIA.

Letters Patent No. 98,953, dated January 18, 1870.

IMPROVEMENT IN BREAKWATERS.

The Schedule referred to in these Letters Patent and making part of the same

I, LOUIS GUTEKUNST, of Philadelphia, county of Philadelphia, and State of Pennsylvania, have invented an Improvement in Breakwaters, of which the following is a specification.

Nature and Object of my Invention.

My invention relates to that class of breakwaters which are erected on sandy coasts, to prevent the inroad of the sea, and consists of a wall and a supporting-buttress so constructed as to be readily and economically erected, with but little labor, and without the necessity of employing skilled mechanics.

Description of the Accompanying Drawing.

Figure 1 is an elevation, partly in section, of my improved breakwater;

Figure 2, a plan view;

Figure 3, a detached view, drawn to an enlarged scale, showing the manner in which the timbers are fitted together; and

Figure 4, a modification of fig. 3.

General Description.

Before proceeding to particularly describe my invention, I will refer to the necessity, which exists on many sandy coasts, of preventing the gradual encroachment of the sea, which results from the constant removal of portions of the land by the action of the waves.

The portion of the land most affected generally lies between high and low-water marks, where the waves strike the beach, pass up the inclined surface and recede, carrying with them particles of sand, which are washed away by the under-currents.

Owing to the unstable character of the foundation, it is impossible, at any reasonable expense, to erect breakwaters of masonry or other heavy material, and it has heretofore been customary to build or anchor caissons, weighted with stones, on the shore, near the low-water line.

This mode, while effective in most instances, is objectionable, as it requires the services, in building and securing the caissons, of expert mechanics, so that the erection of a breakwater of any extent, by private parties, is seldom practicable.

My improved breakwater, which is open to none of these objections, consists of two portions, a frame-buttress, A, and a wall, B.

The buttress consists of a series of horizontal beams, a, each supported on and secured to piles b b, which are driven, at suitable distances apart, vertically into the sand, to such a depth as may be necessary to obtain a firm support.

The inner end of each beam a is generally level with or embedded in the sand, but the outer end, which extends forward over the inclined portion of the beach, is at such a height above the latter as to bear against the central portion of the wall B, the lower edge of which rests upon the beach at the low-water line.

The wall is composed of sections c, each of which consists of a series of heavy planks, d d, arranged side by side, to present a continuous surface, and se-

curely bolted to cross-pieces e e, the ends of which are cut away, as shown in fig. 3, so as to overlap or underlap the ends of the cross-pieces of the adjacent sections to which they are bolted.

The outer ends of the beams a are cut away to receive the central cross-pieces e, or, to avoid weakening the beams, the cross-piece e may rest upon the ends of the beams a, as shown in fig. 4.

The wall is securely braced by stay-rods i i, extending from each section to the beams a a, which support the same, as shown in figs. 1 and 2.

When the tide is low, the waves will strike the lower portion of the wall with but little force, which the wall will be enabled to effectually resist by the stays i i, but as the tide rises, and the waves dash with a greater force against the wall, they will strike the central portion of the same, the beams a receiving the full force of the shock and effectually resisting it.

It will be apparent, that owing to the relative arrangement of the buttress and the wall, the latter may be much lighter in weight, and will require less bracing and support than the ordinary wooden breakwaters in which the wall is caused to bear the full force of the waves.

The principal advantages of my improved breakwater, however, are the ease with which it can be, constructed at points distant from the coast, and transported to the latter; the speed and facility with which it can be erected; and its comparatively small cost.

Owing to the limited size of the sections e, they can be readily transported, either by land or water, from the place where they are constructed, which is generally at some distance from the point where they are erected, where facilities for their manufacture can seldom be obtained.

The buttress can be erected by workmen of ordinary skill, and the work can be prosecuted without interruption during any state of the tide, and after the buttress is erected, and the sections C are prepared, the latter can be secured in their positions with great rapidity, and without any other facilities than those which can always be secured at the place of erection.

A breakwater thus constructed, may be erected at a small expense, and the rapid and extensive inroads of the sea, which take place annually on exposed coasts, may thus be effectually prevented.

Claim.

A breakwater, consisting of a buttress A, constructed as described, and a vertical wall, B, bearing at its centre against the horizontal buttress-beams a, and braced and secured to the latter, as set forth.

In testimony whereof, I have signed my name to this specification, in the presence of two subscribing witnesses.
